PULSE COMMUNICATION SYSTEM EMPLOYING PULSE FREQUENCY REDUCTION FOR SIGNALING

Edmond M. Deloraine, New York, and Donald D. Grieg, Forest Hills, N. Y., assignors to Federal Telephone and Radio Corporation, New York, N. Y., a corporation of Delaware

Application October 11, 1943, Serial No. 505,778

6 Claims. (Cl. 179—15)

1

This invention relates to signaling systems and more particularly to signaling systems adapted for use in regular intelligence communication systems.

In the normal telegraph and telephone communication systems using amplitude or frequency modulation, particularly carrier communication systems, the transmission of ringing and the like signaling has generally constituted a relatively complex problem. With the use of modulated impulses for transmission of intelligence, simplified forms of signaling devices are readily possible. Such arrangements are broadly disclosed in the copending application of E. M. Deloraine, entitled "Communication and signaling system," filed on October 4, 1943, Serial No. 504,881.

It is an object of our invention to provide a signaling system of a novel character for use with modulated impulse communication systems.

It is a further object of our invention to provide the signaling system for use in impulse modulation systems wherein the signal receptive means may be connected directly to the output of the demodulating receiver.

Other objects of our invention and specific features thereof will become apparent from a reading of the particular description of an embodiment thereof made with reference to the accompanying drawing, in which:

Fig. 1 is a block circuit diagram of a system embodying our invention; and

Fig. 2 is a set of curves used in explaining the operation of the system of Fig. 1.

In Fig. 1, a multiplex impulse communication system is diagrammatically shown comprising a source of synchronizing waves 10 supplying control waves to impulse modulator 11 and through phase shifters 14 and 15 to other impulse modulators 12 and 13. It should be understood that while only three channels are shown in the present system, other modulators may be provided to furnish as many channels as the line can properly carry. The outputs from impulse modulators 11, 12 and 13 are applied to a common line 18, preferably a coaxial line or other high frequency carrier line. In place of a transmission line, radio transmission may be used if desired. These impulses because of phase shifters 14 and 15, are inter-leaved one with the other to provide a resultant wave of impulses 1, 2 and 3, as shown in curve a of Fig. 2.

These impulses are applied to a synchronizing control oscillator or other means of any suitable type 20 and to channel selectors 21, 22 and 23. At the same time, synchronizing control output

2

is applied to channel selector 21 and over phase shifters 24 and 25 to channel selectors 22 and 23, to select the desired channel before demodulating the received impulses in the normal manner. The selected impulses from channel selector 21 are applied over line 26 and condenser 27 to the voice or other frequency reproducing demodulating apparatus 31. Similarly, the output from each channel selector 22 and 23 is applied over lines 26A, 26B and condensers 27A, 27B, respectively, to other demodulators 32, 33. The impulses 1, 2 and 3 are modulated, preferably in time position, in accordance with the sound signals to be transmitted. Thus, the sound signals derived from the impulses are applied at the output of demodulators 31, 32 and 33. It is clear that pulse amplitude modulation may be used instead of time modulation, if desired, in which case the demodulators will serve to reproduce the sound frequency envelope directly. Thus, in normal operation, the separate channels are used for separate communications.

In accordance with our invention, when it is desired to signal to a receiving station to indicate that intelligence signals are to be transmitted or for some other purpose, a frequency divider is provided to reduce the number of impulses in that channel to a ringing or signaling frequency. To this end, turning first to the channel using modulator 11 and channel selector 21, we provide a frequency divider 16 controlled by synchronizing source 10. This frequency divider comprises a square wave generator 16a and a mixer and clipper 16b to provide a wave of the form such as 30 shown in curve b which is added to the impulse train serving to elevate every fourth impulse from the output of modulator 11. These elevated impulses are then clipped at the level indicated by clipping line 31a so that only every fourth impulse from modulator 11 is applied to line 18.

It should be understood that the factor of frequency division is shown only by way of illustration. Normally, the number of impulses applied to the line would be in the order of twelve thousand per second. It would usually be preferable then to reduce the frequency to some value depending on the ringing connection used.

Where the output of the demodulator is used to supply the ringing energy a value such as 150 or 300 pulses or cycles per second would be used, so that the frequency division normally would be much greater than that shown in its simplified form for purposes of illustration.

These impulses of lower frequency are then selected in either of two manners. In one manner, the divided pulses are led directly to the ringing device utilizing the wave 32a to which the received impulses are added, as shown by curve c, Fig. 2. At the output of channel selector 21 only the impulses of channel 1 are selected, and since these are at a low frequency level as indicated by the elevated impulses of curve c, the output of channel selector 21 will provide this low signaling frequency as indicated by the impulses above the clipping level 33a of curve c. Condenser 27 preferably is selected so that it does not pass this low frequency and all the low frequency is therefore shunted over low pass filter 28 to signaling buzzer 29. Thus, the signaling unit may be connected directly across line 26. Instead of providing a separate low pass filter 28, buzzer 29 may readily be made of such frequency characteristics that it will respond to these low frequency signals but will serve as a choke to the normal higher frequencies. Alternatively a second means of utilizing the signaling characteristics of the device is to allow the audio output of demodulator 31 rather than the direct pulses to energize relay 29. Under this condition an audio tone corresponding to the divided pulse frequency will be obtained at the output of the demodulator and which is of sufficiently low frequency to be passed by filter 28 and excite the buzzer 29. For this type of operation, connection is made to the buzzer 29, from the output side of demodulator 31.

It is thus clear in our invention that we have provided a very simple form of signaling system. It is only necessary to operate switch 17 to a position including in series frequency divider 16 in order to signal to demodulator 21. When the signaling is not taking place, switch 17 is returned to a position to directly connect modulator 11 to line 18 without the frequency divider 16 in series.

In order similarly to signal from modulators 12 and 13 we provide frequency dividers 16A and 16B connectable into the line by means of switches 17A, 17B, respectively. The signaling frequencies produced by frequency dividers 16A and 16B are selected in demodulators 22 and 23, respectively, and applied to the respective outputs at 28A, 29A and 28B, 29B to signal these other selected stations. It should be noted that a single frequency divider may be used for all channels in place of the individual dividers by providing the proper switching arrangement.

It is clear that any desired form of frequency divider may be used in place of the type diagrammatically illustrated. Furthermore, other forms of signaling equipment than the simple buzzers may be provided, if desired, at the receiving end.

While we have described above the principles of our invention in connection with specific apparatus, and particular modifications thereof, it is to be clearly understood that this description is made only by way of example and not as a limitation on the scope of our invention as set forth in the objects of our invention and the accompanying claims.

What is claimed is:

1. In a transmission system of the type wherein intelligence is transmitted by modulation of a train of impulses repeated at a cadence above the highest frequency of said intelligence, a system of signaling comprising means for effectively selecting certain discrete impulses of said train at regularly recurring intervals, whereby

there are provided in said train substantially only impulses recurring at a given low cadence frequency, receiver means for receiving said impulses, and signal means responsive to said impulses of said low cadence frequency coupled directly to said receiver means for producing said signals, said means for effectively selecting said impulses comprising a frequency divider including a square wave generator, a mixer and a clipper, means coupling the output of said generator to said mixer and clipper, and means for selectively inserting and removing said frequency divider from the circuit.

2. A transmission system comprising a source of impulses for producing impulses having a normal spacing providing a cadence frequency for said impulses higher than the frequency of intelligence normally transmitted thereby, a transmission medium for said impulses, receiver means for receiving said impulses after transmission over said medium, a frequency divider for reducing said cadence frequency to a lower signal frequency cadence, means for selectively inserting said frequency divider between said impulse source and said medium, and means in the output of said receiver means responsive to said signal cadence frequency impulses to produce a signal indication at said receiver.

3. In a communication system of the type wherein intelligence is transmitted from a transmitter through a transmission medium in the form of a train of modulated impulses repeated at a cadence above the highest frequency of said intelligence to a receiver; a signaling arrangement comprising a selector for selecting discrete impulses of said train at regularly recurring intervals whereby there is provided at the output of said selector a train of impulses recurring at a cadence equal to the period of a lower frequency, means for selectively coupling said transmitter either directly to said transmission medium or through said selector to said medium, and signal means at said receiver responsive to said impulses of said lower frequency coupled to said receiver for producing said signals.

4. A transmission system comprising a source of impulses for producing impulses having a normal spacing providing a cadence frequency for said impulses higher than the frequency of intelligence normally transmitted thereby, a transmission line for said impulses, receiver means for receiving said impulses after transmission over said line, a frequency divider for reducing said cadence frequency to a lower signal frequency cadence, means for selectively inserting said frequency divider into said line, and means in the output of said receiver means responsive to said signal cadence frequency impulses to produce a signal indication at said receiver.

5. In a multi-channel communication system wherein communication is carried on between a plurality of transmitters and a corresponding plurality of receivers over a common transmission medium, each of said transmitters providing a train of impulses spaced apart by a regular time interval to produce a cadence frequency above the highest frequency at which intelligence is normally to be transmitted, and each of said receivers serving to receive and demodulate the corresponding train of impulses from the transmitters and apply it to an individual output line, a system for selectively signaling from any one of said transmitters to the corresponding receiver comprising a frequency divider means for each said transmitter to provide for reduction of said

cadence frequency to a signal frequency, means for selectively connecting each frequency divider in the output of its corresponding transmitter, and signal responsive means tuned to respond to said signal frequency, coupled to the output transmission line at each receiver.

6. A multi-channel communication system according to claim 5 further comprising a synchronizing wave source at the transmitter terminal and a second synchronizing source at the receiver terminal for normally synchronizing the operation of said transmitters and said receivers, and means coupling said synchronizing source at said transmitter terminal in phase controlled relation to said frequency dividers to synchronize their operation with their respective transmitters.
